UNITED STATES PATENT OFFICE

110,386

DESIGN FOR A CHAIR

James F. Eppenstein, Chicago, Ill.

Application February 28, 1938, Serial No. 75,470

Term of patent 3½ years

To all whom it may concern:

Be it known that I, James F. Eppenstein, a citizen of the United States, residing at Chicago, in the county of Cook and State of Illinois, have invented a new, original, and ornamental Design for Chairs, of which the following is a specification, reference being had to the accompanying drawing, forming part thereof.

The figure is a perspective view of a chair, showing my new design.

I claim:

The ornamental design for a chair, as shown.

JAMES F. EPPENSTEIN.
